US00D991038S

(12) **United States Design Patent** (10) **Patent No.:** **US D991,038 S**
Filosa (45) **Date of Patent:** **** Jul. 4, 2023**

(54) **PACKAGING CONTAINER**

(71) Applicant: **Method Products, PBC**, San Francisco, CA (US)

(72) Inventor: **Louis Filosa**, San Francisco, CA (US)

(73) Assignee: **Method Products, PBC**, San Francisco, CA (US)

(**) Term: **15 Years**

(21) Appl. No.: **29/802,344**

(22) Filed: **Aug. 4, 2021**

(51) LOC (14) Cl. **09-01**

(52) U.S. Cl.

USPC **D9/522**

(58) **Field of Classification Search**

USPC D9/522, 530, 542, 560, 565, 420, 424, D9/432, 499

CPC A45D 40/00; A45D 2040/0012

(57) **CLAIM**

The ornamental design for a packaging container, as shown and described.

DESCRIPTION

FIG. 1 is a top perspective view of a packaging container showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of a packaging container showing the claimed design;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines in the figures show portions of the packaging container that form no part of the claimed design.

The shade lines in the figures show contour and not surface ornamentation.

1 Claim, 16 Drawing Sheets
